US00D835993S

(12) **United States Design Patent** (10) **Patent No.:** **US D835,993 S**
(45) **Date of Patent:** **** Dec. 18, 2018**

(54) **CONTAINER WITH LID**(71) Applicant: **The Procter & Gamble Company**,
Cincinnati, OH (US)(72) Inventors: **Nicole Lynn Briggs**, West Chester, OH
(US); **Richard Michael Girardot**, West
Chester, OH (US); **Christopher Robert
Kopulos**, Cincinnati, OH (US); **Brian
Joseph Sullivan**, Milford, OH (US)(73) Assignee: **The Procter & Gamble Company**,
Cincinnati, OH (US)(***) Term: **15 Years**(21) Appl. No.: **29/590,001**(22) Filed: **Jan. 6, 2017**(30) **Foreign Application Priority Data**

Jul. 18, 2016 (WO) 968193301

Primary Examiner — Karen S Acker*Assistant Examiner* — Omeed Agilee(74) *Attorney, Agent, or Firm* — Gregory S.
Darley-Emerson(57) **CLAIM**The ornamental design for a container with lid, as shown and
described above.

DESCRIPTION

FIG. 1 is a perspective view of a container with lid;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines and the areas within the broken lines depict
portions of the container with lid that form no part of the
claimed design.**1 Claim, 7 Drawing Sheets**| (56)	References Cited
